UNITED STATES PATENT OFFICE.

KARL RÖGER, OF BERLIN, GERMANY, ASSIGNOR TO MERGENTHALER LINOTYPE COMPANY, A CORPORATION OF NEW YORK.

TYPOGRAPHICAL COMPOSING-MACHINE.

1,161,161.

Specification of Letters Patent. Patented Nov. 23, 1915.

Application filed July 14, 1915. Serial No. 39,923.

To all whom it may concern:

Be it known that I, KARL RÖGER, a subject of the German Emperor, residing at 33 Teltowerstrasse, Berlin, in the Empire of Germany, have invented new and useful Improvements in Typographical Composing-Machines, of which the following is a specification.

In matrix composing and line casting machines provided with a plurality of superposed magazines, it has already been proposed to bring the different magazines alternately into operative position by swinging or raising and lowering them, and of this class of machine there are constructional forms in which there is only a single distributor to distribute the matrices into the particular magazine which, at the time, is in working position, and other constructional forms in which there are two distributors working simultaneously, and in these last-named constructional forms it is possible to compose matrices from both magazines in one and the same line, thus producing what is known as lines of mixed matter. Usually in such a case, the magazines are pivotally mounted in bearings so that they are free to be swung about an axis situated near the distributors, their lower ends being raised and lowered alternately into engagement with the plate entrance, while their upper ends remain in operative connection with the distributors. The use of more than two distributors for such pivoted magazines is not found to be convenient, and the construction of such an arrangement is scarcely feasible, because during the swing, the positions of the upper ends of the magazines change too much relatively to the distributors; for this reason such machines have not usually been provided with more than two magazines. Although it is sufficient for ordinary purposes, to compose mixed matter from two magazines, it frequently happens that instead of mixing thin and bold face type, thin type has to be mixed with italic; in other words, it is frequently necessary to use a magazine which contains a particular font alternately

with different matter of another font. In 50 the known mode of construction of such machines it was necessary for this purpose to change the matrices in the second magazine, which involved a considerable loss of time. The present invention obviates this difficulty 55 owing to the fact that several magazines are arranged one above another on a frame in such a way that each of them together with the next higher or the next lower one, can be brought into operative position at will, 60 so that mixed matter can be produced as desired from any two adjacent magazines of the column.

The drawings show examples of two constructional forms of the invention. 65

In these drawings:—Figure 1 is a side elevation of a constructional form of the machine, with three magazines, while in Fig. 2 four magazines are shown. Fig. 3 shows the changing device of the so-called font-distinguisher, on an enlarged scale. 70

In the drawing 1 is the machine frame and 2 a frame supported in bearings on the machine frame, by a pivot or pivots 3. On the frame 2 lies a further frame 4, which 75 is pivoted to the frame 2 by a pivot 5, and supports the magazines 6, 7 and 8. Any two adjacent magazines can be placed in operative communication with the two distributors 9, (in Fig. 1 it is the two upper 80 magazines 6 and 7 which are so in communication), and the lower or delivery ends of those magazines can alternately be brought into operative register with the assembler entrance 11, by operating the hand lever 10, 85 which is connected with a cam 12 which turns the frame 4 together with the column of magazines about the axis of the pivot 5; in the drawing, it is the middle magazine (7) which is thus shown as in working position. If the handle 10 be turned in the necessary direction, the uppermost magazine (6) comes into operative communication 90 with the assembler entrance 11, and thus matter can be composed from both of the 95 magazines 6, 7 alternately. The distribution into the magazines is effected by the distributors 9 in the known manner.

To enable the middle magazine 7 to be used conjointly with the lower magazine 8, a plate 13 is provided between the frame 4 and the column of the magazines, which 5 plate can be raised parallelly with the said frame, by means of parallel lever arms 14 mutually connected by a link 15, and thereby move the whole column of magazines in a direction perpendicular to its inclination, 10 the magazines being guided during this movement by means of downward projections 16 on the plate 13, engaging with rollers 17 on the frame 4. A hand lever 18 in connection with the lever arms 14, serves 15 for raising the column of magazines through a distance equal to that between corresponding parts, say the top surfaces, of any two adjacent magazines, so that the two lower magazines 7 and 8 can be brought into oper- 20 ative register with the distributor and thereby provide for the composition of mixed matter from those magazines; by moving the hand lever 18 in the reverse direction, the magazine column can be lowered to 25 bring the two magazines 6, 7, into composing position.

The changing of the magazines may be effected in the known manner, for instance by swinging the frame 2 rearwardly about 30 the pivots 3, removing the magazines to be changed, from the said frame, and substituting for them the desired new magazines.

In the constructional form according to Fig. 2, four superposed magazines, 6, 7, 8 35 and 19, are provided, of which any two immediately adjacent ones can be simultaneously brought into composing position. The lever 10, as in the before described example, which serves for effecting an operative substitution of one for the other of the two magazines which are in operative position is, in this example, arranged in the same manner as in the said before described example, excepting that the parallel lever 40 arms connected with the hand lever 18 for raising and lowering the magazine column are arranged so that the plate 13 can be adjusted thereby to three different heights, and consequently either the two upper magazines, or the second and third, or the third and fourth, of such magazines, can be brought into operative connection with the distributor.

As is already known, each of the matrices 55 has in its foot a special notch whose position varies according to the particular magazine to which that matrix belongs. As, according to the present arrangement, each of the middle magazines must work together with 60 the two distributors, there must be an arrangement for the automatic shifting of the font-distinguisher which registers with the notches in the respective matrices. Such a device can be of simple construction, and

can, for instance as shown in Figs. 2 and 3, 65 consist of a lever 20 which, by means of a disk 21 provided with preferably adjustable projections or cams 22, can be adjusted to different positions, and the upper end of which is in connection with a rod 23, which 70 carries the font-distinguisher 24, 25 which coöperate with the notches in the feet of the matrices. By turning the disk 21 angularly, the rod 23 is adjusted, and with it the font-distinguisher 24, 25. The turning of the 75 disk 21 is effected by a cord 26 wound around it, and fastened at one end to the column of magazines, and having attached to its other end a weight 27, so that in every position of the magazine column the particular cam 22 8 appropriate to that position, engages with the lever 20.

The invention can be employed in connection with three distributors and more than three superposed magazines, and in such an 85 arrangement there will always be three magazines in position from which composition can be effected.

Having described my invention, I declare that what I claim and desire to secure by 90 Letters Patent is:—

1. In a typographical machine, the combination with a series of magazines, a plurality of adjacent distributors arranged one behind another, and an assembler receiving 95 device, of means whereby different selected pluralities of adjacent magazines may be brought into operative relation to the distributors, and means whereby any magazine of the selected plurality may be 100 brought into operative relation to the assembler receiving device.

2. In a typographical machine, the combination of an assembler receiving device, a plurality of distributors, a series of magazines movably mounted so that different selected pluralities thereof may be brought into operative relation to the distributors, and means whereby any magazine of the selected plurality may be 110 brought into operative relation to the assembler receiving device.

3. In a typographical machine, the combination of a fixed assembler receiving device, a plurality of distributors, a series of magazines movable as a whole to bring a selected plurality of magazines into operative relation to the distributors, and means whereby the magazines may be given a further movement to locate one or another of the magazines of the selected plurality in operative relation to the fixed assembler receiving device.

4. In a typographical machine, the combination with a series of magazines, a plurality of distributors, and a fixed assembler receiving device, of a supporting frame for 115 the magazines movable to bring different 120

selected pluralities thereof into operative relation to the distributor, and a further frame supporting the other and pivotally mounted so that one or another of the magazines of the selected plurality may be swung into or out of operative relation to the assembler receiving device.

5. In a typographical machine, the combination of three or more superposed magazines each provided with a series of escapements, and movably arranged so that any pair of adjacent magazines may be brought into operative relation to two adjacent distributor, the said distributor, a single assembler receiving device, into operative relation to which either magazine of said pair can be brought and devices for actuating the escapements of the selected magazine.

6. In a typographical machine, the combination of three or more superposed magazines, distributing mechanism, assembling mechanism and means whereby when desired the distributing mechanism may be connected to any selected plurality of adjoining magazines, and any one of that plurality may be connected to the assembling mechanism.

7. In a typographical machine, the combination of a plurality of superposed magazines, distributing mechanism, assembling mechanism, means adapted to move the column of magazines rectilinearly to bring any selected plurality of them into operative connection with the distributing mechanism, and means adapted to move the magazines curvilinearly to bring any magazine of the selected plurality into operative connection with the assembling mechanism.

8. In a typographical machine, the combination of a plurality of superposed magazines, distributing mechanism, assembling mechanism, a frame supporting the column of magazines, means operative to move this frame rectilinearly to bring any selected plurality of the magazines into operative connection with the distributing mechanism, a pivoted frame supporting the rectilinearly movable frame, and means operative to move this pivoted frame curvilinearly to bring any magazine of the selected plurality into operative connection with the assembling mechanism.

9. In a typographical machine, the combination of a plurality of superposed magazines, distributing mechanism, assembling mechanism, means adapted to move the column of magazines to bring any selected plurality of them into operative connection with the distributing mechanism, means adapted to move the magazines to bring any magazine of the selected plurality into operative connection with the assembling mechanism, a font distinguisher discriminating between the matrices for the respec-

tive magazines, and means adapted to automatically adjust the font distinguisher when the magazines are moved.

10. In a typographical machine, the combination of a plurality of font distinguishers controlling the delivery of matrices to different distributor, and means whereby said distinguishers may be adjusted in unison.

11. In a typographical machine, the combination of a plurality of font distinguishers controlling the delivery of matrices to different magazines and adjustable in unison to different operative positions, and automatic means for effecting the adjustment of said distinguishers.

12. In a typographical machine, the combination with three or more magazines, a plurality of distributor therefor, and means whereby different selected pluralities of magazines may be operatively connected to the distributor, of a plurality of font distinguishers controlling the delivery of matrices to the respective distributor, and automatic mechanism for adjusting the font distinguishers to different operative positions simultaneously to correspond to the different selected pluralities of magazines.

13. In a typographical machine, the combination with three or more magazines, a plurality of distributor therefor, and means whereby different selected pluralities of magazines may be operatively connected to the distributor, of a plurality of font distinguishers controlling the delivery of matrices to the respective distributor, and mechanism for adjusting the font distinguishers to different operative positions to correspond to the different selected pluralities of magazines.

14. In a typographical machine, the combination with distributing mechanism, assembling mechanism, and a series of magazines arranged face to face therebetween, of means whereby different selected pluralities of adjoining magazines may be operatively connected with the distributing mechanism, and means whereby any magazine of the selected plurality may be connected with the assembling mechanism without disturbing the operative connection between said plurality and the distributing mechanism.

15. In a typographical machine, the combination with a plurality of adjacent distributor, an assembler receiving device, and a series of magazines arranged therebetween, of means whereby different selected pluralities of adjoining magazines may be operatively connected with the distributor, and means whereby any magazine of the selected plurality may be brought into operative relation to the assembler receiving

device without disturbing the connection of said plurality with the distributers.

16. In a typographical machine, the combination with a plurality of distributers, an assembler receiving device, and a series of magazines movably arranged so that different selected pluralities thereof may be operatively connected with the distributers, of means whereby the magazines may be given a further movement to bring one or another of the selected plurality into opera-

tive relation to the assembler receiving device without disturbing the operative connection of said plurality with the distributers.

In witness whereof I have hereunto set my hand in the presence of two witnesses.

KARL RÖGER.
